BATHING CAP

Ina Kathleen de Wet, Mount Marlow, P. O.
Witmos Rail, Union of South AfricaApplication August 22, 1932, Serial No. 629,946,
and in the Union of South Africa January 2,
1932

5 Claims. (Cl. 2—68)

The present invention relates to bathing caps; the object being to construct a cap which provides an effective water-tight seal between the cap and the head of the wearer so that the latter's hair is kept dry.

The invention is illustrated in the accompanying drawing in which

Fig. I is a back view of one form of cap, partly sectioned.

10 Fig. II is a longitudinal section on II—II Fig. I. Fig. III is a side elevation of another form of cap.

Fig. IV shows the cap in use.

Referring to Figs. I and II, 2 indicates a bag made of rubber or other thin flexible material and of such size and shape as to enclose the hair of the wearer.

At the mouth of the bag is formed a rubber rim 3 of appropriate thickness to be put under substantial tension when stretched. Said rim is straight in the sense that its edge 4 or any transverse cross section of it lies in one plane, and so that when pulled into position to lie on the wearer's forehead in front and on the neck 25 below the hair at the back, it remains in one plane, as indicated in Fig. IV. It is thus circumferentially tensioned at all points of its circumference and correspondingly presses inwardly with substantial pressure at all such points to make an effective water seal all around the head.

The width 5 of the rim is such as to maintain the straight form and also to provide enough area to make the water seal effective; a width of one inch having been found appropriate.

35 To increase the effectiveness of the seal, the inner surface of the rim may be formed with a series of circumferential ribs 6 and grooves 7, the ribs serving to localize the available inward pressure.

40 If desired means are provided for taking up and slackening the rim circumferentially to adjust it to heads of different size and to compensate for stretching of the rim in use. For this

45 purpose in the construction shown the rim is divided at 8 and its two ends are continued to form loose-ended straps 9 which are adjustably secured to one another by such means as the buckle 10.

The water tight seal against the head is maintained between the straps 9 by extending a portion of the bag material as a gusset 11 between the separated ends of the rim proper. Said material is thin enough to fold according to the varying distance between the ends of the rim, without occupying appreciable thickness; and it is

retained in contact with the head by the inward pressure of the straps 9.

A cap as described may be worn alone, or under the commonly used diving cap which has ear pieces connected by a chin strap and is becoming but not water tight because its lower edge is not in one plane and therefore cannot be put under straight tension.

Fig. III shows the Fig. I arrangement modified to give the diving cap appearance. In this case 65 the cap is divided at a circumferential line 12 into separate inner and outer skirts 13 and 14, both united to and forming a continuation of the crown portion 15 and of thin flexible material. The inner skirt is formed at its mouth with the 70 thickened straight rim 3 as already described, for making the water tight seal with the head. The outer skirt is long enough to be pulled down to conceal the inner skirt, as indicated at 16, 16, Fig. III, whilst it is also capable of being turned 75 up as indicated at 17 to leave the rim 3 readily accessible when the cap is being put on. The outer skirt is provided with ear pieces 18 and a chin strap 19 so that the outward appearance is that of the usual diving cap.

I claim:

1. A bathing cap comprising a thin flexible bag adapted to cover the wearer's hair, a thickened elastic rim forming for the greater part of its circumferential length a unitary structure with the bag, continuations of the rim ends extending as loose-ended straps, and means for adjustably securing the straps to one another, a portion of the thin bag material extending as a continuation of the rim between the points of 90 the rim from which the straps diverge.

2. A bathing cap comprising a thin flexible bag adapted to cover the hair of the wearer and divided towards its mouth into separate inner and outer thin flexible skirts, the inner skirt terminating in a straight thickened rim and the outer skirt having a curved mouth including depending ear-pieces.

3. A bathing cap comprising a thin flexible bag adapted to cover the wearer's hair and divided towards its mouth into separate inner and outer thin flexible skirts, the inner skirt having a straight mouth, a straight thickened rim at said mouth, and circumferential ribs on the inner surface of the rim, the outer skirt having a curved mouth including depending ear-pieces.

4. A bathing cap comprising a thin flexible bag adapted to cover the wearer's hair and divided towards its mouth into separate inner and outer thin flexible skirts, the inner skirt having

a straight mouth, a straight thickened rim at said mouth, circumferential ribs on the inner surface of the rim, and means for adjusting the circumferential length of said rim, the outer skirt having a curved mouth including depending ear-pieces.

5. A bathing cap comprising a thin flexible bag adapted to cover the wearer's hair, a thickened flat strap-like elastic rim forming for the

greater part of its circumference a unitary structure with the bag and adapted to make direct contact with the wearer's head, loose-ended straps forming continuations of the rim ends, and means for adjustably securing the straps to one another so as to adjust the tension of the rim when the latter is stretched around the head.
